BY *Frederick W. Parsons* ATTYS.

UNITED STATES PATENT OFFICE.

FREDERICK WILLIAM PARSONS, OF CLEVELAND, OHIO, ASSIGNOR TO THE PARSONS & PARSONS COMPANY, OF CLEVELAND, OHIO, A CORPORATION OF OHIO.

COLLAR FOR NECKWEAR.

1,102,431.

Specification of Letters Patent.

Patented July 7, 1914.

Application filed June 23, 1908. Serial No. 439,662.

To all whom it may concern:

Be it known that I, FREDERICK WILLIAM PARSONS, a citizen of the United States, residing at Cleveland, in the county of Cuyahoga and State of Ohio, have invented certain new and useful Improvements in Collars for Neckwear, and do declare that the following is a full, clear, and exact description of the invention, which will enable others skilled in the art to which it applies to make and use the same.

My invention relates to improvements in collars for neck wear, and the improvement consists in the construction substantially as herein shown and described and more particularly pointed out in the claims.

In the accompanying drawings, Figure 1 is a front perspective view of the collar, and Fig. 2 is a top edge view of one end thereof with the immediate edge of the collar broken away from the front rearward to disclose the three-ply construction thereof. Fig. 3 is a cross sectional elevation on line 3—3, Fig. 1, and Fig. 4 is a cross sectional elevation corresponding substantially to line 4—4, Fig. 1.

The construction herein comprises the collar proper C of lay-down type or variety and a strip or tab D located therein between the band or inner portion of the collar —2— which comes next to the neck and the outer or turn-down portion —3—, as shown. The object herein is to provide the collar with buttonhole extensions 4 at the respective ends of the collar which are free from the collar at its immediate end edges α and γ , or the edges of the band and lay-down portions respectively, and substantially free from the turn-over edge and angle or corner δ , to the end that the said edge or corner δ shall be under no undue strains. The said inner tab or extension D is shown in this instance as extending entirely around within the collar its full length, and is provided with a buttonhole 6 at its rear and center in the place where the usual rear buttonhole comes in a collar, and the band or neck portion of the collar is recessed or cut out at 8 from its lower edge upward to about half its own depth or the full width of the said part D at the rear and for some distance upon both sides of the hole 6, so that the collar is only two layers deep in said recessed portion, and by having a relatively wide recess the bend and adaptation of the collar

about the neck is rendered easy, and convenience for buttoning through the hole 6 is facilitated. The said part D furthermore has substantially the same width throughout the greater portion of its length or body portion as shown herein, but gradually widens at its upper edge toward its ends or extremities, where it is made as wide relatively as the usual tab or buttonhole extensions upon collars and is otherwise constructed or shaped to resemble such tabs or extensions and thus avoid any unusual appearances in the collar when it is upon the neck. It will be observed also that the upper edge of said extension or tab portions 4 is free from the immediate corner or angle δ of the collar inward for some distance, say to about 7, Fig. 2, so that no strain comes upon this angle portion of the collar in handling the said tabs or extensions or in the wearing of the collar. Under these favoring conditions it has been found that a collar will wear almost indefinitely and not necessarily sustain breakage or injury at the point δ , while with the strain that otherwise comes to the said buttonhole extensions the buttoning and unbuttoning of the collar is rendered much more easy and convenient than formerly. In this connection it will, of course, be understood that the two parts C and D, which constitute the complete collar as it goes to the market and is worn, are cemented or otherwise adhered or secured together over at least portions of their contacting surfaces so as to make them practically one for service and to keep the parts in right relations, and any suitable adhesive or other means may be employed for this purpose. By cutting the said recess 8 relatively as wide or slightly wider than the strip D and by leaving said strip free to bend or flex between the edges of the recess regardless of the lay-down portion of the collar, I provide for easy buttoning and unbuttoning the collar at this point, and this adds materially to the popularity of the collar among users.

The construction of collar as heretofore described is essentially a two-piece collar and may obviously be modified without materially departing from the spirit of the invention which involves in the main, the use of a supplemental band or strip having buttonhole portions wherewith free and easy

buttoning and unbuttoning is afforded and the wear on the collar at the fold line is practically eliminated.

What I claim is:—

- 5 1. A lay-down collar and a separate strip secured therein of relatively narrower width at its middle than at its ends to provide widened tabs at the front of the collar and a free upper space between the folds of the
10 collar at the rear and having buttonholes in its ends and its middle portion.
- 15 2. A collar having a lay-down portion and a strip of greater length than the collar laid between the band and the said lay-down portion and having ends of substantially the same width as the band and provided with buttonholes, the band of the collar being recessed at its middle and rear and the said

strip having a buttonhole exposed in said recess.

3. A two-piece collar for neck wear comprising an inner neck band portion having an outer turn-down portion, and a supplemental strip of narrower width at its middle than at its ends secured to said inner band portion and having buttonhole ends of substantially the same width as said band portion and adapted to overlap and have free play in respect to the end edges thereof.

In testimony whereof I sign this specification in the presence of two witnesses.

FREDERICK WILLIAM PARSONS.
